UNITED STATES PATENT OFFICE.

JOHN F. METTEN, OF PHILADELPHIA, PENNSYLVANIA, ASSIGNOR TO THE WILLIAM CRAMP & SONS SHIP & ENGINE BUILDING COMPANY, A CORPORATION OF PENNSYLVANIA.

TURBINE-NOZZLE.

1,213,930.

Specification of Letters Patent. Patented Jan. 30, 1917.

Application filed July 3, 1914. Serial No. 848,731.

To all whom it may concern:

Be it known that I, JOHN F. METTEN, a citizen of the United States, residing at Philadelphia, in the county of Philadelphia and State of Pennsylvania, have invented 5 certain new and useful Improvements in Turbine-Nozzles, of which the following is a full, clear, and exact specification.

This invention relates to steam turbines, 10 and has particular reference to multi-stage turbines of the impulse type, wherein the several stages are separated by diaphragms having passages or nozzles for passing the steam into the successive stages. These dia- 15 phragms, especially where there is full peripheral admission of steam, as in marine turbines, have been built heretofore in such manner that the strain due to the steam pressure is transmitted to the casing 20 through the nozzle or blade structure itself. This requires that the nozzle structure be constructed strong enough to transmit the total axial pressure on the diaphragm to the casing.

25 It is the object of this invention to relieve the nozzle structure of this strain by making it in segments separate from the diaphragm itself, or the locking ring or other part which is interposed between the diaphragm 30 and the casing and which transmits the strain. Thereby, a number of advantages are realized both in the original construction of the turbine, and in case it is later desired to inspect or repair the nozzle 35 blading. In manufacture, the advantages reside in constructing the nozzle blading separately from the diaphragm, thereby avoiding strains in the blading, and also permitting the design and material of the 40 blading to be such as not to corrode or wear, and of best efficiency. In case of inspection or repair, any nozzle ring segment can be removed and replaced without dismantling the entire structure.

45 In the preferred form herein shown, the diaphragm consists of a disk having a grooved rim secured to its periphery, and between the diaphragm and the casing is interposed a segmental nozzle carrying ring, 50 to which latter ring the segmental nozzle rings and blades are separably attached. Thereby, the nozzle rings and blades are not subjected to the axial strain due to the total pressure on the diaphragm, they can be 55 better designed of more suitable material,

and in case of damage new blades can be easily supplied. As herein shown, the ring carrying the separable nozzle ring segments and blades is slidable between the dia- 60 phragm and the casing, and to readily permit this, the diaphragm and casing grooves, or either of them, are provided with non-rusting composition liners, so that the lower rings can be slid around in the casing when the top is removed.

65

The invention is illustrated in the accompanying drawings, wherein—

Figure 1 is an elevation, partly in section, of one of the removable nozzle carrying rings; Fig. 2 is a longitudinal section; 70 Fig. 3 is a detail on an enlarged scale; Fig. 4 is a perspective view of one of the blades; and Figs. 5 and 6 are detail views on an enlarged scale of the nozzle carrying rings. A represents a casing containing the shaft 75 B, to which are secured the wheels C, each of which carries two or more rows of blades E. Between these rows of blades E are stationary blades G fixed to the casing. Between successive wheels C are stationary 80 diaphragms H, each of which comprises a central packing ring I attached to the center of the disk H and a peripheral ring K overlying the ring I and attached to disk H on the opposite side, so as to reduce the 85 overall length of the turbine. The ring K is provided with a circumferential groove L, and the casing A has an internal circumferential groove M in which grooves channel liners N, O, respectively of non-rusting 90 metal are secured as by screws P. As will be seen, these grooves are comprised between parallel radial planes, and overlie 95 each other so as to receive the segments of a slidable nozzle carrying ring Q. The segments of this ring Q each consist of separated bridge pieces R, between which the steam passes to the nozzles, together with internally projecting tongues S on which tongues inner and outer blade carrying segments T, U slide. The bridge pieces R are made of sufficient strength to transmit the entire steam pressure on the diaphragm directly to the casing for the purpose of relieving the nozzle structure thereof. This 100 not only permits the nozzle structure to be relieved of manufacturing strains, as for example where the nozzle blades are cast in their supporting structure, but also permits 105 a greater freedom of design of the nozzles 110

themselves, both as to choice of material and their number, shape, proportions, etc. The nozzle blades V are shown in Fig. 4, as having top and bottom projections W 5 which pass through holes in the rings T, U, and the projections may be headed over or riveted to the rings T, U. The segmental rings T, U, together with the blades V therefore constitute the nozzle segments, 10 which can be successively slid in position on the tongues S of the nozzle carrying rings Q. The rings T, U are provided with inner shoulders as Z which bear against the tongues S, and when all of the nozzle ring 15 segments have been assembled in one-half of the casing, or any other segment thereof, they can be fastened therein by riveting over the corners X on the beveled corners of the tongues S. The segments of the 20 nozzle carrying rings Q are fastened in position by screws Y tapped into the casing, which screws become accessible when a portion of the casing is removed.

The nozzle carrying ring Q with bridges 25 R is preferably made of steel, while the nozzle structure comprising the segmental rings T, U, with or without blades V, is preferably made of drawn bronze. The liners N, O, may also be of bronze. This material is 30 not subject to corrosion and weakening when subjected to the effect of high pressure steam moving at high velocity, and furthermore it can be accurately finished to the desired shape and dimensions. Thus the danger 35 of broken blades is avoided, and the nozzles do not change in shape and design from corrosion, as happens when they are built of steel. As the nozzle structure is assembled without casting the parts together, objectionable 40 stresses are not developed due to the pouring of hot metal, and every part can be made alike and examined before being inserted in the turbine, so that there will not be any loose blades or weak connections. This 45 also permits the nozzle blades to be of varying thickness, which adapts them to give the best form of steam passage at all parts of the nozzle, which is especially desirable in impulse turbines which effect a major portion 50 of the steam expansion in the stationary nozzles.

The present invention is also advantageous in case of necessitating inspecting or repairing a nozzle section or sections. When 55 the casing is removed, or the nozzle carrying ring slid around in the lower half of the casing, the damaged nozzle blades can be removed by cutting off the blades from between the segmental rings, permitting the 60 rings to be removed between the bridges in the carrying rings and then a new section can be inserted. If a section of nozzle blading 65 to be removed lay directly in front of one of the bridges it would be necessary to cut out the nozzle blading far enough to one

side or the other of the bridge to permit of the pieces being removed, and then two new short sections could be inserted. By this invention it is comparatively easy to cut wherever desired and fit short pieces in to fill the gap, because even short sections when inserted would be equal in strength to the remainder of the nozzle ring, the ends of the containing ring being fitted close between the ends of the original section and the 70 blades of the new short section being riveted in the same manner as on the original long section. The invention is especially applicable where full peripheral admission is employed, but it will be seen that blank sections could be inserted in the nozzle carrying rings if desired, so as to give only partial admission.

This application is a continuation in part of my application, Serial No. 780,682, filed 85 July 23, 1913.

It will be understood that the particular construction herein shown is but one example of the manner in which the invention may be carried out, and that various modifications and changes may be made without departing from the scope of the appended claims.

Having thus described my invention, I declare that what I claim as new and desire to 95 secure by Letters Patent is:

1. In a turbine, the combination with a casing, of a diaphragm, a separate nozzle carrying element engaging the casing and the diaphragm to lock the latter, and a separate nozzle structure mounted in said nozzle carrying element.

2. In a turbine, the combination with a casing, of a diaphragm, a separate nozzle carrying element slidably engaging the casing and the diaphragm to lock the latter, and a separate nozzle structure mounted in said nozzle carrying element.

3. In a turbine, the combination with a casing, of a diaphragm, a divided nozzle carrying ring slidably mounted between the casing and the diaphragm, and a segmental nozzle structure mounted in said ring.

4. In a turbine, the combination with a casing, of a diaphragm, a nozzle carrying ring slidably interlocking with both the casing and the diaphragm whereby the nozzle ring holds the diaphragm against displacement, and a nozzle structure comprising concentric rings and radial blades carried by said ring.

5. In a turbine, the combination with a casing around its inner surface, of a diaphragm, a segmental nozzle carrying ring formed to slidably interlock with the diaphragm and the grooved casing to hold the diaphragm in position and be slidably removable independently of the diaphragm, and a segmental nozzle structure mounted in said ring.

6. In a turbine, the combination with a casing having a removable section, of a diaphragm, a segmental nozzle carrying ring slidably interlocking the casing and the diaphragm whereby a segment within the casing can be pushed around and removed through an open portion of the casing, and a series of nozzle segments slidably inserted in said ring whereby a nozzle segment can be removed independently of the others.

7. In a turbine, the combination with a diaphragm, of a separate nozzle carrying ring segment interlocking therewith on its periphery, and a nozzle structure removably mounted in said ring and interlocking therewith by a tongue and groove connection.

8. In a turbine, the combination with a diaphragm, of a nozzle carrying ring segment interlocking with said diaphragm, and a nozzle structure removably mounted in said ring and interlocking therewith.

9. In a turbine, the combination with a casing, of a diaphragm, a removable nozzle carrying segment between the casing and the diaphragm, said segment being capable of removal without removing the diaphragm, and a nozzle structure removably mounted in and interlocking with said segment.

10. In a turbine, the combination with a casing, of a shaft therein, a diaphragm encircling said shaft, said casing being divided on a longitudinal plane through the shaft, a nozzle carrying ring separable from the diaphragm and separably fitted to the casing, said ring being divided into sections, removable fastenings for securing said ring sections to the casing sections, and a nozzle structure removably mounted in said nozzle ring.

11. In a turbine, the combination with a casing, of a shaft therein, a diaphragm encircling said shaft, said casing being divided on a longitudinal plane through the shaft, said diaphragm comprising a nozzle carrying ring divided into a plurality of segments and slidably interlocking the casing and the diaphragm, and a nozzle structure divided into a plurality of segments, said nozzle structure being slidable in said nozzle ring.

12. In a turbine, the combination with a sectional casing and a diaphragm, of a nozzle carrying ring segment fastened to and removable with a casing section, a second nozzle carrying ring segment slidably removable independently of the remainder of the casing and the diaphragm and a nozzle structure slidably mounted in said nozzle carrying ring.

13. In a turbine, the combination with a sectional casing, of a segmental nozzle carrying ring having separated bridges and fastened between the casing and the diaphragm, and a nozzle structure mounted in said nozzle ring at one side of said bridges.

14. In a turbine, the combination with a casing, of a built-up diaphragm comprising a hub, a dished disk carried by said hub, a nozzle containing ring segment removably interposed between said disk and the casing, and a separate nozzle structure comprising nozzle blades, mounted in said segment.

15. In a turbine, the combination with a casing, of a diaphragm of less diameter than the casing, a nozzle structure container between and mechanically connecting said diaphragm with said casing, and a nozzle structure removably mounted in said interposed container.

16. In a turbine, the combination with a casing, of a diaphragm of less diameter than said casing, a nozzle carrying structure comprising an apertured bridged ring connecting the diaphragm and the casing, and removable nozzles in said ring.

17. In a turbine, the combination with a casing, of a diaphragm, a nozzle structure container mechanically connected with said diaphragm and said casing, and a nozzle structure removably mounted in said container, said nozzle structure comprising blade holding segments and nozzle blades secured between said segments.

18. The combination with a casing, of a diaphragm, a segmental nozzle container mechanically connecting said diaphragm with said casing, said container comprising inner and outer segments secured together by bridges or posts, between which posts steam may pass, and a nozzle structure slideable in said container, said nozzle structure comprising blade holding segments and nozzle blades secured between said segments.

19. The combination with a casing, of a diaphragm, a segmental nozzle container mechanically connecting said diaphragm with said casing, said container comprising inner and outer segments secured together by bridges or posts, between which posts steam may pass, and a nozzle structure slidably mounted in said container, said nozzle structure comprising blade holding segments and nozzle blades secured between said segments, the material of said container being of one kind and the material of said nozzle structure being of a less corrodible material.

20. In a turbine, the combination with a casing having an internal projection, of a diaphragm having a peripheral projection spaced within said casing projection, a connecting ring removably interlocking with said projections to mechanically connect said casing and said diaphragm, said connecting ring having a steam passage, and nozzle blades mounted on said connecting ring in said steam passage.

21. In a turbine, the combination with a nozzle support comprising spaced concentric rings and bridge pieces, of a plurality of spaced concentric rings carried thereby, and

- a plurality of blades between and interlocked with said latter rings.
22. In a turbine, the combination with a nozzle support comprising spaced concentric rings and bridge pieces, of a plurality of spaced concentric rings carried thereby, and a plurality of blades between and interlocked with said latter rings, said rings and blades being slidably separable as a unit from said support. 5
23. In a turbine, a nozzle element comprising spaced perforated segments, and blades between said segments having shanks extending through said perforations and headed over to fasten said blades and segments rigidly together. 10
24. In a turbine, a nozzle element comprising spaced perforated segments, blades between said segments having shanks extending through said perforations and headed over to fasten said blades and segments rigidly together, and a segmental annular support carrying said nozzle element. 15
25. In a turbine, a steel nozzle support, and composition ring segments connected by composition blades, slidable in said support. 20
26. In a turbine, a casing, a diaphragm, a noncorroding liner thereon, a nozzle support slidably engaging said liner, and means transmitting strain from the diaphragm to the casing. 25
27. In a turbine, a casing having a non-corroding liner, a diaphragm having a non-corroding liner, and a nozzle support slidably engaging said liner. 30
28. In a turbine, a nozzle element comprising concentric supporting segments, blade carrying segments adapted to be headed to engage said concentric segments, and blades carried by said segments. 35
29. In a turbine, a nozzle element comprising a support, a blade carrying segment having a shoulder engaging said support to oppose movement in one direction and headed engagement with said support to oppose movement in the opposite direction, and blades carried by said segment. 40

In testimony whereof I affix my signature, in presence of two witnesses.

JOHN F. METTEN.
